No. 36,562.

Patented September 22, 1903.

UNITED STATES PATENT OFFICE.

HENRY H. COLLINS, JR., OF PHILADELPHIA, PENNSYLVANIA.

DESIGN FOR A CARD-MOUNT.

SPECIFICATION forming part of Design No. 36,562, dated September 22, 1903.

Application filed August 21, 1903. Serial No. 170,373. Term of patent 3½ years.

To all whom it may concern:

Be it known that I, HENRY H. COLLINS, Jr., a citizen of the United States, residing in Philadelphia, Pennsylvania, have invented a new, original, and ornamental Design for a Card-Mount, of which the following is a specification.

My design is fully shown in the accompanying drawings, in which—

I claim—

The ornamental design for a card-mount, substantially as shown in the accompanying 15 drawings.

In testimony whereof I have signed my name to this specification in the presence of two subscribing witnesses.

HENRY H. COLLINS, JR.
